UNITED STATES PATENT OFFICE.

EPHREM FÉLIX VALIQUET, OF MONTREAL, QUEBEC, CANADA, ASSIGNOR OF ONE-FIFTH TO JOSEPH FELIX DESMARAIS, ONE-FIFTH TO OMER FRANCOIS LEFEBVRE, AND ONE-FIFTH TO JOSEPH CHARLES DESMARAIS, ALL OF MONTREAL, CANADA.

WINDING-INDICATOR.

1,213,438.

Specification of Letters Patent. Patented Jan. 23, 1917.

Application filed December 2, 1915. Serial No. 64,760.

To all whom it may concern:

Be it known that I, EPHREM FÉLIX VALIQUET, a subject of the King of Great Britain, and residing at 23 Atwater avenue, in the city of Montreal, in the Province of Quebec, Canada, have invented certain new and useful Improvements in Winding-Indicators; and I do hereby declare that the following is a full, clear, and exact description of the same.

The invention relates to a new and useful improvement in a winding indicator, and it is the primary object of the invention to provide a novel device of this character, wherein the numerals on the dial will automatically disappear at a determined time, thereby indicating that it is necessary to rewind the motor of the watch.

It is also the object of the invention to provide a novel device of this character which will be simple in construction, efficient and advantageous in practice and inexpensive to manufacture.

With the above objects in view, the invention consists in the details of construction and in the novel arrangement and combination of parts to be hereinafter more particularly referred to.

In describing the invention in detail, reference will be had to the accompanying drawings forming part of this specification, wherein like characters of reference denote corresponding parts in the several views, in which—

Figure 1 is a front elevation of a watch illustrating the special dial applied thereto, the numerals being visible. Fig. 2 is a rear elevation of the watch, the movements of the watch having been removed and the invention applied on the inner face of the dial. Fig. 3 is a front elevation of the watch, illustrating the special dial applied thereto, the numerals being invisible, thus indicating that the watch must be rewound.

Fig. 4 is a cross section view on line A—A in Fig. 2. Fig. 5 is an enlarged detail view of the spring-held operating lever. Fig. 6 is an enlarged view of the spring-held releasing lever. Fig. 7 is an enlarged view showing the detent and its allied parts clearly and without the watch case in front of the parts.

Like numerals of reference indicate corresponding parts in each figure.

In the drawings, 1 denotes the casing of an ordinary watch and 2 is the dial, disposed within its circumference, having a plurality of circular openings 3, through which will appear the numerals 4, which are printed on the face of a circular band 5. The said band 5 is adapted to slide in the slide-way 6 formed in the plate 7. It may be here mentioned that in swinging the circular band 5, the numerals will disappear under the dial 2 as illustrated in Fig. 3, thereby indicating that the watch must be rewound. The plate 7 is provided with elongated slots 8, 9 and 10, which abut within the slide-way or channel 6. On the inner face of said plate 7 is suitably mounted the gear 11, which is provided with a pin 12, secured within its circumference, said pin 12 being adapted to disengage the releasing pawl 13, which is pivoted to a suitable bracket 14 and held by the spring 15 in engagement with the pin 16. Said pin 16 is secured to the inner side of the circular band 5 and projects through the opening 9 provided in the plate 7. The said pawl 13 is provided at its free end with a notch 17, which is adapted to engage a corresponding projection on the pin 16.

18 is a tension spring pivoted to the pivot 19 at one end and at the other end to the pin 20, which is secured on the inner face of the circular band 5 and projects through the slot or opening 9.

21 is the operating pawl pivotally secured on the pivot 22, which in turn is secured on the circular band 5 and projects through the opening 10 in the plate 7, said pawl 21 being provided at one end with a hook 23, which is adapted to engage the gear 24, mounted on the ordinary shaft of the watch spring. At the other end, the said pawl 21 is provided with an outwardly projecting point 26, which is adapted to contact with the flat spring 27 and cause the hook 23 to engage the teeth of the gear 24.

28 is a flat spring suitably secured on the plate 7 and adapted to press the pawl 21 out of engagement with the gear 24.

29 is a pinion mounted on the minute wheel and adapted to rotate the gear or hour wheel 30. Said hour wheel 30 is so arranged that it will engage the gear 11 and cause same to rotate.

When the watch is in operation, the

minute wheel 29 and the hour wheel 30 will accordingly rotate. The hour wheel co-acting with the gear 11 will rotate the said gear and cause the pin 12 provided on said gear 11, to engage the pawl 13 and cause it to release the pin 16. The spring 18 which is connected at one end to the pivot 19 on the plate 7 and at the other end to the pin 20 on the circular band 5 will cause said circular band to rotate and thereby push the numerals on the said circular band out of vision, and, therefore, will have the effect to advise or signal that the watch must be rewound.

It may be here mentioned that the gear 11 can be made to turn twice in 24 hours or more or less and the time to cause the releasing pawl 13 to disengage the pin 16 can be easily fixed. The advantage of rotating the gear 11 by means of the hour wheel is that, should the watch become out of order, or should the time be corrected, it will automatically at the same time correct the time for releasing the pawl 13. Immediately on winding the watch, the shaft 25 will cause the gear 24 to rotate and it will thereby pull the pawl 21 which is in engagement with the said gear 24 when the numerals are out of vision, also rotating the circular band 5, which will retake its primary position, the releasing pawl being immediately pressed down by the spring 15, will engage the pin 16 and lock the circular band in its normal or primary position. By providing for the releasing of the circular band 5 considerably before the watch is completely unwound any variation of the speed for being allowed to run while the tension of the spring is very weak is prevented, and by providing for the immediate action of the circular band 5 to come into its normal place as the watch is being wound up, will prevent any over-exertion of the spring, and, therefore, eliminate trouble which may arise from unnecessary tension on the spring.

In the invention herewith described, the numerals on the band 5 will become invisible regularly, at a specified time, no matter if the watch is rewound or not.

The preferred form is herewith described and it is thought that the description will be found to be sufficiently clear.

What I claim is:

1. An indicator for watches comprising a main watch dial provided with a plurality of circumferential openings, a rotary dial provided with numerals which in its normal position will permit the said numerals to be visible through the openings provided in the main watch dial, means to rotate said dial and thereby cause the numerals to become invisible and means to rotate said rotary dial back to its normal position on winding the watch, substantially as described.

2. An indicator for watches comprising a main watch dial provided with a plurality of circumferential openings, a fixed plate provided with a circular groove adjacent to its edge, a circular dial provided with time indicating numerals sliding in said circular groove, said circular dial being spring-held in its normal position, means to release said dial and thereby cause the numerals to become invisible and manual means to rotate said circular dial back to its normal position, substantially as described.

3. An indicator for watches comprising a fixed main watch dial provided with a plurality of openings adjacent to its circumference, a circular dial provided with a plurality of time indicating numerals, a fixed plate provided with a circular groove adjacent to its edge having a number of openings, said groove being adapted to receive the said circular dial, a gear mounted on said fixed plate, a pawl engaging said circular dial, means to rotate said gear, means to disengage said pawl from said dial and means to rotate said circular dial back into its normal position, substantially as described.

4. An indicator for watches, comprising a fixed main watch dial provided with a plurality of openings adjacent to its circumference, a circular dial provided with a plurality of time indicating numerals, a fixed plate provided with a circular groove adjacent to its edge, having a number of openings, said groove being adapted to receive the said circular dial, a gear mounted on said fixed plate, a pawl pivotally secured to said plate engaging a pin mounted on said circular dial passing through one of said openings in the groove of said fixed plate, means to rotate said gear, means to disengage said pawl from said pin, means to rotate said circular dial and means to rotate said circular dial back to its normal position, substantially as described.

5. An indicator for watches, comprising a fixed main watch dial provided with a plurality of openings adjacent to its circumference, a circular dial provided with a plurality of time indicating numerals, a fixed plate provided with a circular groove adjacent to its edge, having a number of openings, said groove being adapted to receive the said circular dial, a gear mounted on said fixed plate, a pawl pivotally secured to said plate engaging a pin mounted on said circular dial passing through one of said openings in the groove of said fixed plate, means to rotate said gear, a spring secured to said fixed plate at one end and at the other end secured to said pin and means to rotate said circular dial back to its normal position, substantially as described.

6. An indicator for watches, comprising a fixed main watch dial provided with a plu-

- rality of openings adjacent to its circumference, a circular dial provided with a plurality of time indicating numerals, a fixed plate provided with a circular groove adjacent to 5 its edge, having a number of openings, said groove being adapted to receive the said circular dial, a gear mounted on said fixed plate, a pawl pivotally secured to said plate engaging a pin mounted on said circular dial 10 passing through one of said openings, in the groove or fixed plate, means to rotate said gear, a spring secured to said fixed plate at one end and at the other end secured to said pin, a gear mounted on the shaft of the 15 watch actuating spring, a lever, adapted to engage said gear pivotally secured to a pin mounted on said circular dial, projecting through one of the openings provided in the fixed plate and means to disengage said 20 pawl from said gear, substantially as described.
7. An indicator for watches, comprising a fixed main watch dial having a plurality of openings adjacent to its circumference, a 25 circular dial provided with a plurality of time indicating numerals, a fixed plate provided with a circular groove adjacent to its edge, having a number of openings through 30 its surface, said groove being adapted to receive the said circular dial, a gear mounted
- on said plate, provided with a lug adapted to disengage a spring-held pawl secured on said fixed plate normally engaging a pin mounted on said circular dial projecting through one of the openings in said groove, 35 said gear being actuated by the hour wheel mounted on the cannon pinion, a spring secured to said fixed plate at one end and at the other end secured to said pin, thereby causing said circular dial to rotate to its 40 secondary position when released by the said spring-held pawl, a gear mounted on the shaft of the watch actuating spring, a pawl pivotally secured at one end to a pivot mounted on said circular dial projecting 45 through one of the openings provided in the groove in the fixed plate, the outer end having the shape of a hook, said pawl being normally disengaged from said gear, means to cause said pawl to engage said gear when 50 winding the watch and thereby actuate the circular dial from its secondary position to its normal position, substantially as described.

Signed at Montreal, Quebec, Canada, this 55
3rd day of November 1915.

EPHREM FÉLIX VALIQUET.
